UNITED STATES PATENT OFFICE.

CARL H. THORNBALDE, OF SEATTLE, WASHINGTON.

OIL BURNER.

Application filed November 19, 1924. Serial No. 750,879.

My invention relates to oil burners of that type in which is employed a generator heated by the burner jets, and in which the oil is heated to gasification before being discharged.

The object of my invention is to generally improve the character and the operation of such a burner and specifically to produce a design which is a composite burner employing a plurality of independently operable burner devices which may be operated either altogether or separately, as desired, each being designed for its own particular use.

The special features of my invention which are new may be determined from a study of the drawings and the following specification.

The accompanying drawings illustrate my invention as embodied in the type of construction which I now prefer. It will, however, be evident that this design may be modified in many details without really departing from the spirit of my invention.

Figure 1 is a top or plan view of my burner, having certain portions thereof broken away and in section to better illustrate details of its construction.

Figure 2 is a section taken upon a plane represented by the broken line 2—2 of Figure 1.

Figure 3 is a section taken substantially upon the plane indicated by the broken line 3—3 of Figure 1.

The composite burner here illustrated shows two separate burner units, these being of essentially like construction, the principles of their construction and operation being alike. Each of these burners employs a mixing chamber having burner jets mounted thereon, a generator which lies alongside of the mixing chamber and is heated by jets therefrom, and a communicating conduit or passage which conveys the gas as discharged from the generator to and into the mixing chamber. In the burner as illustrated, 1 represents the principal burners as a whole, and 10 the secondary or auxiliary burner. The mixing chamber 11 of the main burner is shown as being of substantially square cross section, although the cross sectional shape of this burner may be made anything which best suits the needs of the burner. The type of burner employed is that which has a series of circular holes in its walls, in which holes are placed disks 12 which are of a re-

fractory material and provided with a considerable number of perforations 13.

These perforations produce the discharge of a large number of jets of mixed air and vaporized oil and may be placed at the top 60 of the burner or the sides, as desired. A series of such burner jets 13 are shown as placed at one side of the mixing chamber and these discharge directly upon the generator tube 2.

The generator tube 2 is supported in guides or eyes as 20, formed at the side of the casting which contains the mixing chamber and has at its discharge end a sleeve 21 in which is formed a small jet orifice. This 70 discharges into a flue or channel 14 formed in this end of the main casting in which the mixing chamber is formed. This curves, making a substantially half-circular bend and discharges into the end of the mixing 75 chamber. In one side wall of this flue is a hole 15, located close alongside of the discharge end of the generator.

The jet discharged from the generator draws air through the opening 15 to mix 80 therewith and form the combustible gas. To prevent ignition of the combustible gas at the point where it is discharged from the generator, I prefer to employ a flange 16 which constitutes an apron interposed between the air inlet opening 15 and the burner jets. Such apron will largely tend to prevent the flashing of the flame from the burner jets around to the air inlet opening 15. The flange 16 may be carried out to such an 85 extent as to engage the side walls of the fire pot in which the burner is placed. It also serves the purpose of holding the body of the burner away from the side walls a sufficient amount to prevent undue restriction of the space leading to the air inlet opening 15. That is, by the use of such flange it is impossible to place the burner near enough to the side wall but that ample area for the supply 90 of air is available.

The particular arrangement of the burner jets relied upon for supplying the heat is largely immaterial. In the arrangement of the burner shown I have employed a circular table 17 at each end of the burner, this being provided with a group of burner jets 13.

Beneath the generator 2, which is in the form of a tube lying alongside the burner, is a priming trough 22, into which may be 110

placed gasoline, alcohol or any other easily ignited fluid the burning of which will heat the generator tube sufficiently to gasify the kerosene or other less volatile oil which may be used as the fuel. I prefer to have the mixing chamber 11 given a slight slope towards the front end of the burner and to connect a pipe as 3 with this end of the burner, to serve as a drain pipe to convey therefrom, any oil which may be passed, thereinto, from the burner, due to incomplete gasification or to condensation in the mixing chamber. I also prefer to have the priming trough 22 located sufficiently below the level of the bottom of the mixing chamber that any oil which may be found in this mixing chamber will flow by gravity into the priming trough where it will be ignited.

In order to control this discharge pipe a stop cock or valve 30 may be placed therein. This stop cock may be left permanently open where it is so connected with the priming trough or may be normally kept closed, as desired. If left open any oil which is left in the mixing chamber will at once flow to the priming trough and by action of the side jets 13' will be burnt, thus adding to the heating of the generator. If, therefore, the generator becomes cooled or is not sufficiently heated to thoroughly gasify the oil passing therethrough, oil will accumulate in the mixing chamber and will be discharged into the priming trough and by its burning therein will furnish additional heat to the priming tube, and this will tend to correct the discharge of oil into the mixing chamber so that such irregularity and imperfection of operation tends to correct itself.

The tube 2 which forms the generator is mounted in a hole provided in an arm or lug 20, extending from the main burner casting, in such manner that it may be adjusted lengthwise of itself. A screw 23 or other device may be employed for holding it in adjusted position. I have found by experiment that the position of the discharge from the generator tube relative to the air inlet opening 15 has an effect upon the action of the burner. By adjusting the generator tube so that the discharge end thereof is extended farther into the passage 14, a richer mixture is obtained as the suction effect produced upon the air is less than when the discharge end of the generator is moved farther back. In this way a certain measure of control may be had over the richness of the mixture being employed.

The secondary burner 10 is of essentially the same construction as the main burner 1. The generator tube 2, however, is placed over the mixing chamber and the main heating surface is placed on one side, as is clearly shown in Figure 2. In a burner of

this sort as placed in an ordinary cook stove or range, the secondary burner 10 is placed at the rear side of the fire pot, where it will directly heat the wall which separates the fire pot from the oven.

The generator tube 2 of the secondary burner is also located where special burner jets 13' of which two only are shown, will impinge upon one end of the generator tube. These two burner jets are the means employed for priming or preliminarily heating the generator of the secondary burner. As a matter of convenience these two burner jets are permitted to burn whenever the main burner is being used. At times it is not desired to use the secondary burner. In this case the action of the burner jets 13' would cause the end of the generator to be overheated and possibly burnt out. To prevent such action I provide a shell, which consists of a piece of sheet metal 4, bent into such shape that one end thereof will embrace and permit it to slide upon the generator 2, while another portion thereof extends downward as a wing which may be interposed between the burner jets 13' and the generator tube. While such a shell may become burnt out, it is of cheap character and may be easily replaced.

The discharge end 21 of the generator discharges its jet into a curved tubular passage, which curves downward and discharges into the mixing chamber 11' of the secondary burner. With this I prefer to form an air inlet opening, as 50, in the bottom wall of such chamber immediately under the discharge jet. Also a second opening, as 51, is provided at one side thereof. I also provide a flange 52 extending laterally so as to protect these openings, both to prevent their being closed by placing the burner too close to the wall of the fire box, and also to prevent the flashing of the flame around the corners so as to ignite the discharged jet before it enters the mixing chamber. As further precaution to prevent such action, a plate 53 may be secured to the outer edge of this flange and extend downward so as to form a thorough protection.

With the above type of burner, use of the main burner 1 will suffice for ordinary cooking or heating purposes. If, however, the oven is to be used and the heat provided by the main burner is insufficient, the secondary burner may be brought into use. After the secondary burner has been ignited, the main burner may be turned off if a low heat in the oven is desired.

Each of these burners is provided with its own separate oil supply pipe, as 31 and 32. The control of the valves for the two generators is preferably by the use of a key wrench which may be placed upon the squared ends 34 of the valve stems. Sepa-

rate shut-off control for the two oil supply pipes 31 and 32 is employed so that each burner may be cut off without affecting the other.

5. What I claim as my invention is:

1. An oil burner having a main and an auxiliary burner set, each set containing a mixing chamber extending lengthwise thereof, the mixing chamber of the auxiliary set 10 being positioned just below and to one side of the mixing chamber of the main burner, a generator tube for the main burner positioned at the side thereof which is away from the auxiliary burner, a generator tube 15 for the auxiliary burner positioned at the opposite side of the main burner and above the auxiliary mixing chamber, the mixing chamber for the auxiliary burner having burner jets in its side face which is away 20 from the main burner and the mixing chamber of the main burner having generator heating discharge jets at opposite sides positioned to heat the generator tubes for both burners.

25. 2. An oil burner having a main and an auxiliary burner set, each provided with a mixing chamber having burner orifices in a side face, the mixing chamber of the main burner being located close above and at one 30 side of the mixing chamber of the auxiliary burner, a generator tube for the main burner located at that side of the main burner which is away from the auxiliary burner, a priming trough below said generator tube, 35 a generator tube for the auxiliary burner located above its mixing chamber and alongside the mixing chamber of the main burner, the mixing chambers of each burner having gas discharge openings positioned to 40 heat its respective generator, and the mixing chamber of the main burner having gas discharge openings positioned to heat the generator of the auxiliary burner.

3. An oil burner having a main and an auxiliary burner set, each provided with a mixing chamber having burner orifices in a side face, the mixing chamber of the main

burner being located close above and at one side of the mixing chamber of the auxiliary burner, a generator tube for the main burner 50 located at that side of the main burner which is away from the auxiliary burner, a priming trough below said generator tube, a generator tube for the auxiliary burner located above its mixing chamber and alongside 55 the mixing chamber of the main burner, curved conduit members connecting the ends of each generator tube with the like end of its mixing chamber and having an air inlet opening at its receiving end, the mixing chambers of each burner having gas discharge openings positioned to heat its respective generator, and the mixing chamber of the main burner having gas discharge 60 openings positioned to heat the generator of the auxiliary burner.

4. An oil burner having a main and an auxiliary burner set each provided with a mixing chamber disposed alongside each other with the mixing chamber of the auxiliary burner immediately below and alongside of the like chamber of the main burner, the mixing chamber of the auxiliary burner having burner discharge openings at the side face which is away from the main 75 burner and generator heating openings in its upper face, a generator tube extending lengthwise of the mixing chamber of the auxiliary burner over the discharge orifices in its upper face, and alongside of the mixing chamber of the main burner, said latter mixing chamber having burner discharge 80 openings towards one end positioned to heat the generator tube of the auxiliary burner, a protective shield movably lengthwise of 85 said generator tube and adapted to protect it from the said jets from the main burner, and a generator tube alongside of the mixing chamber of the main burner, said mixing chamber having burner jets in its side 90 face for heating its generator tube.

Signed at Seattle, King County, Washington, this 1st day of November, 1924.
